UNITED STATES PATENT OFFICE.

ALEXANDER T. KASLEY, OF SWISSVALE, PENNSYLVANIA, ASSIGNOR TO THE WESTINGHOUSE MACHINE COMPANY, A CORPORATION OF PENNSYLVANIA.

PUMP.

No. 921,118.

Specification of Letters Patent.

Patented May 11, 1909.

Application filed May 26, 1905. Serial No. 262,494.

To all whom it may concern:

Be it known that I, ALEXANDER T. KASLEY, a citizen of the United States, and a resident of Swissvale, in the county of Allegheny and State of Pennsylvania, have invented a new and useful Improvement in Pumps, of which the following is a specification.

This invention relates to blowers and pumps, and more particularly to centrifugal or rotary blowers and pumps.

A distinction I make between blowers and compressors and pumps is that pumps are utilized for liquids, while blowers and compressors are utilized for gaseous or elastic fluids.

Since the invention hereinafter set forth is generic, I do not wish to limit it to any division of the broad term "pump," but intend that this application shall be broad enough to cover all centrifugal or rotary pumps whatsoever they may be termed by the trade.

Since the advent of the steam turbine on a commercial footing, it has been the desire of many manufacturers to obtain a centrifugal pump capable of operating efficiently at desirable turbine speeds whereby the pump and turbine can be direct connected.

Up to the time of this invention I believe it has been next to impossible to build a centrifugal pump with any range of application to meet the demands of steam turbine work. The conditions in most cases and those presenting the greatest number of obstacles to the manufacturer of efficient pumps have been high power, high speed and low head. For high speed and low head the necessary peripheral speed gives a diameter of the runner or pump impeller that is often much less than the size of the pump intake pipe, if the velocities in the intake pipe are kept within reasonable limits. I am aware that numerous schemes have been proposed to the end of overcoming these difficulties, but with all of those with which I am familiar either the cost of the schemes or the low efficiencies of the same render them valueless.

In attempting to devise a centrifugal pump which would meet the speed requirements of the steam turbine, I have discovered what I believe to be a new principle, and in developing this principle I find that I am enabled to produce centrifugal pumps,

blowers and compressors which are not only capable of being driven at the ordinary steam turbine speeds, with good efficiencies, but are more efficient than any of the centrifugal pumps, blowers and compressors 60 which have been heretofore devised for any conditions.

In the drawings accompanying this application I have illustrated two pumps, each embodying the principle of this invention, 65 and each adapted for different duties.

Figure 1 is a view in sectional elevation of what may be termed a "high head pump," while Fig. 2 is a view in sectional elevation of what may be termed a "low head pump." 70

Since the new principle involved in each is the same, it is deemed advisable to embody them in one application, but since the design of the several elements entering into the make-up of the two pumps is different it 75 has been deemed advisable not to give the correspondingly named parts like reference characters.

Broadly, each of the forms illustrated embodies a rotatable impeller and rotatably 80 mounted diffuser vanes which are adapted to be rotated in the same direction as the impeller, but at a slower speed, by the impelled fluid or by the fluid leaving the outlet of the impeller. By means of these rotatable diffuser vanes the fluid impinging thereon strikes with much less shock, and therefore with less loss of energy than if the diffuser vanes were stationary as they are in ordinary centrifugal pumps. 85

Fig. 1 illustrates a pump designed to be direct coupled to a steam turbine running at 3600 R. P. M. and is adapted to pump against a 600 foot head. 90

The pump consists of a casing 3, provided with suitable inlets 4 and a discharge outlet 5. The impeller 6, which is shown of a form now common and which takes the fluid, which hereafter for the sake of brevity will be termed water, at both sides near its axis, 100 is rigidly mounted on a shaft 7 adapted to be direct connected to the turbine shaft.

Surrounding the impeller and between it and the stationary casing 3 is a casing 8 rigidly secured to a suitably journaled idler 105 shaft 9. The connection between the casing 8 and the shaft 9 consists of a web 10, the several portions of which are formed in the nature of blades. Corresponding blades 11 are carried by the casing 8 adjacent to the 110

inlet of the impeller opposite to the inlet adjacent to the blades 10.

The stationary casing as shown is provided with a volute or snail-shell chamber 12 (which may or may not be provided with diffuser vanes), and with which the discharge opening 5 communicates. The rotatable casing 8 between the outlet of the impeller and the inlet to the volute is provided with 10 diffuser vanes 13.

The impeller, by means of its vanes, raises the water to a high velocity, and by means of the rotatable diffuser vanes 13 a part of the velocity energy of the water expelled 15 from the impeller is converted into pressure energy prior to its entry into the volute, and since the diffuser vanes 13 are allowed to rotate the shock of the water impinging thereagainst is mitigated, and the loss of the 20 energy is lower or less than it would be if the diffuser vanes were stationary.

It will be seen that the rotating casing 8 will act as a diffusing member even if unprovided with diffuser vanes; the centrifugal 25 force of the freely rotating water causing the pressure to increase and the velocity to decrease. The gain in this case is in the reduction of the friction between the water and the walls of the casing 8 on account of the 30 smaller relative velocity.

By means of the blades 10 and 11, which are driven through the casing 8 by means of the diffuser vanes 13, the water is given a velocity prior to its entry into the impeller, 35 and the final velocity is thereby stepped up gradually, and it will be seen that there will be no pressure increase between the several steps. By thus gradually bringing the water up to speed the loss of power due to shock is 40 greatly reduced.

Since the pressure produced in a centrifugal pump consists of two parts, one due to the centrifugal force of the water in the runner, and the other due to the velocity with 45 which the water strikes the diffuser vanes, by allowing the casing to rotate at $\frac{1}{2}$ the speed of the impeller, and to be 1.4 times its diameter the impact pressure as the water strikes 50 13 will be approximately $\frac{1}{4}$ what it would be if the casing 8 were stationary. There is also an impact where the water leaving 13 strikes the volute which will be $(\frac{1}{2} \times 1.4)^2 = \frac{1}{2}$. Therefore the part of the pressure due to the 55 velocity of the water striking the vanes is reduced from 1 to approximately $\frac{1}{4} + \frac{1}{2} = \frac{3}{4}$ and the centrifugal force part will be increased from 1 to approximately $1 - \frac{1}{4}$ thus causing the greater part of the work to be 60 done by the more efficient method.

60 Fig. 2 illustrates a pump designed to be direct connected to a steam turbine running at 3600 R. P. M., and is adapted to pump against a 200 foot head. The pump consists of a stationary casing 14, provided with an 65 inlet 15 and a discharge outlet 16. A runner

or impeller 17, provided with any desired form of blades, is mounted on a shaft 18 adapted to be direct coupled to the turbine. With this pump no stationary casing or volute is employed in the ordinary meaning, 70 though a small volute may be found desirable for conveying the water to outlet 16. A rotatable casing 19, through the agency of the diffuser vanes 20 and supports 21, is mounted on an idler shaft 22. The casing 19, like the 75 casing 8 of the pump illustrated in Fig. 1, carries blades 23 which step up the velocity of the impelled water. The water leaving the impeller is discharged into the rotatable casing 19 and its velocity energy, by means of 80 the diffuser vanes 20, is converted into pressure energy. The casing is so formed that it directs the water inwardly toward the axis of shaft 22 and thereby the head is reduced. The relative velocity of the water passing 85 through the casing 19 and the casing itself, is reduced owing to the fact that the casing revolves in the same direction as the impeller but at a slower speed. The efficiency of this pump as in the one illustrated in Fig. 1, is increased by increasing the centrifugal force 90 component of the pressure pumped at the expense of the impact or the component due to the velocity with which the water strikes the diffuser vanes. By allowing the diffuser 95 vanes to revolve at $1/n$ the speed of the impeller, the centrifugal part is reduced by the centrifugal force of the water in the revolving casing by the factor $1 - (1/n)^2$, and the impact pressure is reduced by the factor $(1 - 1/n)^2$, 100 but if n is greater than 1 then $1 - (1/n)^2$ is greater than $(1 - 1/n)^2$, so that the greater part of the work is done by the more efficient part of the pump. As an illustration, suppose the rotating casing to revolve at about 105 $\frac{1}{2}$ the speed of the impeller then the centrifugal force of the water in the casing acting against the flow will be approximately $\frac{1}{4}$ as great as the centrifugal force in the impeller, so that the resultant pressure will be approximately $(1 - \frac{1}{4})$ or $\frac{3}{4}$, while the pressure due to impact will be reduced to approximately $(\frac{1}{2})^2$ or $\frac{1}{4}$. Thus the centrifugal component becomes three times as great as the impact instead of only being equal to it. The head 110 is hereby reduced to approximately $\frac{3}{4} + \frac{1}{4} = 1$ instead of $1 + 1 = 2$, while the skin friction between the impeller and the water, between it and the casing, could only be approximately $(\frac{1}{2})^3 = \frac{1}{8}$ as great since the relative 115 velocity is $\frac{1}{2}$ of what it was before, so that there is an appreciable saving obtained by reducing the skin-friction. Since the idler shaft 22 is caused to rotate, the energy due 120 thereto is made available and can be used for driving a generator, or for any other purpose desired when the conditions are suitable. In this application I have shown it driving an ordinary low head centrifugal pump 125 which will be connected in parallel with the 130

pump just described. As this ordinary type of pump is now common, no description of the same is deemed necessary, but it will be understood that the discharge outlet of this ordinary pump will communicate with the discharge outlet from the pump illustrated to the left of Fig. 2, and as the shaft 22 will revolve at a relatively slow speed this ordinary type of centrifugal pump may be successfully utilized.

It will be understood that since this invention is generic many modifications may be made from the constructions shown without departing from the spirit of this invention. 15 It will also be understood that a multi-stage pump employing this principle is contemplated, and that an apparatus operating in the reverse manner may be utilized as an efficient form of turbine either for elastic or 20 inelastic fluids.

Having thus described my invention, what I claim as new and useful and desire to secure by Letters Patent is:—

1. In combination in a centrifugal pump, 25 a fluid impeller, rotatable means for imparting velocity to the fluid to be impelled prior to its contact with the impeller, and an agent receiving its energy from the impelled fluid for driving said means.

30 2. In combination in a centrifugal pump, a fluid impeller, rotatable means for imparting velocity to the fluid to be impelled prior to its contact with the impeller, and an agent receiving its energy from the impelled fluid 35 for driving said means at a lower speed than the impeller but in the same direction.

3. In combination in a centrifugal pump, a rotatable impeller, a rotatable agent with which the impelled fluid contacts in its passage 40 between the outlet of the impeller and the pump outlet whereby part of the kinetic energy of the fluid is transformed into pressure energy, and an instrumentality driven from said agent whereby the shock of the 45 fluid prior to its entry to said impeller is mitigated.

4. The combination in a centrifugal pump of a rotatable impeller, a stationary casing provided with an inlet port and an outlet 50 port, a plurality of rotatable blades between said inlet port and said impeller and a plurality of rotatable blades between said outlet port and said impeller.

5. The combination in a centrifugal pump 55 of a rotatable impeller, a stationary casing

provided with an inlet port and an exhaust port, a rotatable casing inclosing said impeller and a plurality of blades mounted on said rotatable casing between said inlet port and said impeller.

60

6. The combination in a centrifugal pump of a rotatable impeller, a stationary casing provided with an inlet port and an exhaust port, an independently rotatable casing inclosing said impeller and a plurality of blades 65 mounted on said rotatable casing between said inlet port and said impeller.

7. The combination in a centrifugal pump of an impeller, a stationary casing provided with an inlet port and an outlet port, a rotatable casing between said stationary casing and said impeller and means operated by said casing for imparting velocity to said fluid prior to its contact with said impeller.

70

8. The combination in a centrifugal pump of an impeller, a rotatable casing for said impeller provided with an inlet port and an outlet port and means operated by said casing for imparting velocity to the fluid to be impelled prior to its admission to the impeller.

75

9. In a centrifugal pump in combination with a fluid impeller, a rotatable means for imparting velocity to the fluid to be impelled prior to its contact with the impeller and an agent within said pump for driving said means.

85

10. In a centrifugal pump in combination with a fluid impeller, a rotatable means for imparting velocity to the fluid to be impelled prior to its contact with the impeller and an agent within said pump for driving said means at a lower speed than the impeller but in the same direction.

90

11. The combination in a centrifugal pump 95 provided with a fluid inlet and a fluid outlet, of a fluid impeller, a plurality of blades between said impeller and said fluid inlet for imparting velocity to the fluid to be impelled prior to its contact with said impeller and means for driving said blades in the same direction as the impeller but at a slower speed.

100

In testimony whereof, I have hereunto subscribed my name this 22nd day of May, 105 1905.

ALEXANDER T. KASLEY.
